(57) **CLAIM**

The ornamental design for the high heel, substantially as shown and described.

DESCRIPTION

FIG. 1 is a rear left side perspective view showing the high heel with our design;

FIG. 2 is a rear right side perspective view showing the high heel with our design;

FIG. 3 is a rear elevation view of the high heel with our design;

FIG. 4 is a right side elevation view of the high heel with our design;

FIG. 5 is a left side elevation view of the high heel with our design;

FIG. 6 is a bottom plan view of the high heel with our design; and,

FIG. 7 is a greatly enlarged section of the high heel with our design as shown in FIG. 3.

The dash dot broken lines in FIG. 7 represent a boundary, used for ease of disclosure and form no part of the claimed design.
